UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 21,616, dated June 7, 1892.

Application filed December 7, 1891. Serial No. 414,340. Term of patent 14 years.

To all whom it may concern:

Be it known that I, GEORGE W. BLAIR, of Pittsburgh, in the county of Allegheny and State of Pennsylvania, have invented a new and original Design for Lamp-Chimneys, of which the following is a full, clear, and exact description, reference being had to the accompanying drawing, which shows in side elevation a lamp-chimney embodying the design.

The design consists in a lamp-chimney having a substantially straight and cylindrical portion above the middle bulge of the chimney and having at the extreme top only a slight flare and provided on its outer side at its upper end with an outer marginal figured band in relief or intaglio.

In the drawing, 2 represents the lamp-chimney, having a portion 3 above the central bulge, which is substantially cylindrical and straight, and having at its extreme top only a slight flare and a marginal figured band on the outer side of the top.

I claim—

The design for lamp-chimneys, substantially as herein shown and described. 25

In testimony whereof I have hereunto set my hand this 4th day of December, A. D. 1891.

GEO. W. BLAIR.
